ATTORNEY.S.

UNITED STATES PATENT OFFICE

EDWARD W. PENDERY, OF NEWPORT, KENTUCKY, ASSIGNOR TO THE HIGGIN MANUFACTURING COMPANY, OF NEWPORT, KENTUCKY, A CORPORATION OF WEST VIRGINIA.

SCREEN INSTALLATION

Application filed April 16, 1928. Serial No. 270,254.

My invention relates to metal frames for screens and windows and the means for fastening them to the main frames of sashes which have already been fixed in place on a building.

It is the object of my invention to provide a means whereby the work and trouble encountered in installing screens on existing window frames can be reduced considerably.

10 It is a further objective to provide an attachment which will compensate for any variations that will occur in the structure to which the frames for screens or windows are to be attached so that all the frames can be 15 made in the factory to standard sizes corresponding to standard windows.

Another object is to provide an attachable means to close off any openings that will occur when a window of the swinging type is 20 opened. This particular type of window presents a problem in that its construction for protection against leakage necessitates projecting elements which invariably interfere with the mounting of screen frames or 25 secondary storm windows.

Prior practice necessitated special care as to dimensions of the screen frames to be attached; and in the majority of cases it has been necessary to alter the existing structure 30 before a screen frame could be attached even after careful coordination of dimensions. When grouting had been carelessly or improperly applied so as to come up almost to the edge of the opening in the frame the 35 labor of workmen was required to clip this grouting away. Further it has been the practice to attach screens to metal window frames, particularly the frames of basement windows, from the outside with screws or bolts.

40 This has necessitated drilling and tapping, operations involving a labor cost, and sometimes leaving the screen removable from the outside. It is an object of my invention to do away with labor in removing grouting or 45 drilling and tapping metal window frames, and to make any fitting operation unnecessary.

The above and other objects to which reference will be made in the ensuing disclosure, I accomplish by that certain combina-

tion and arrangement of parts of which I have illustrated a preferred embodiment.

In the drawings:

Figure 1 is a plan view in section taken along the line 1—1 of Figure 2.

Figure 2 is an elevation in section taken along the line 2—2 of Figure 1.

Figure 3 is an elevation in section showing the attachment for closing the opening made by the water table when a window is opened.

Figure 4 is a perspective view of part of a screen frame with my special adjustable attachment mounted thereon.

I have shown an opening 1 provided in the walls of a building into which a frame 2 for a window is set previous to mounting a sash 3 which is generally hinged and mounted at the top of the frame 2 as shown in Figure 2 at 3^a. The front face 4 of the frame is generally grouted in with concrete 5 indicated in Figure 1, and this concrete, when carelessly applied, frequently makes the frame inaccessible for mounting screens and the like. Even though it were accessible it would be necessary to drill and tap the frame in order to mount any fastening thereon.

With my Z-shaped attachment 6 it is not necessary to tap and drill a window frame. I provide, for attaching the screen, two Z-shaped members 6 which are attached to the screen at the factory by means of screws 8. Slot-like openings for the passage of the screws may be provided in both attaching members if desired; but it is not necessary, and I prefer to provide the slots in both of the attachment members. It will be understood that in ordinary practice one of my attachment members is used upon either side of the screen as will be more fully explained. Since the screws 8 are slidably mounted in a slot in at least one of the strips 6, all that is necessary to widen or contract the screen fastening to fit a window frame is to loosen the screws enough so that the Z-shaped member is free to slide the desired amount.

In use, I cut my Z-shaped members, one for each side of the screen, of such length as will permit them to enter the sides of the window frame. The screen is, of course, held outside the window frame. In Figure 2 it is

shown as projecting beyond the edge of the frame both above and below. But it is to be noted that the screen need not project beyond the edge of the frame along the sides, since the strip will close the lateral spaces. 5 Figure 1 shows the screen coming just to the edge of the opening. It will be understood that my fasteners, instead of being placed along the sides of the screen, can be placed 10 on the top and bottom, or on all four sides, but that when only two strips are used either the top and the bottom, or the two sides of the screen should project beyond the edge of the frame opening to prevent the screen coming through. In other words the screen should be larger in one dimension than the frame opening, though it may be larger in both dimensions if desired.

My fasteners operate to hold the screen in place in the following manner. Reference to Figure 1 will show the fasteners in place. One arm of the Z is attached as noted to the screen, and the other is caused to project within the window frame. The offset of the 25 fastener accommodates the thickness of the metal window frame edge, and the face 1^a lies along the inner side of the frame member. The screen, then is held to the frame by my fasteners upon the inside thereof and the top 30 and bottom of the screen in the construction shown on the outside. The lower edge of both my fasteners at the ends 27 (Figure 2) rest upon the ledge of the frame 26 and support the weight of the screen.

35 All that is necessary in installing my screen is to loosen the screws holding one of the fasteners in place, place the screen in position with the face 6^a of the other fastener lying on the inside of the window frame, then slide the loosened fastener toward the edge of the 40 screen until its face 6^a lies on the inside of the frame member. The screws are then tightened, and the screen is in place. All adjustments and dimensions have been taken care 45 of in the factory, and the only operation of the workman installing the screen is the one just outlined.

In the case where a water table 10 projects from the sash beyond the main window frame 50 I have provided an L-shaped member 11^a which fastens to the bottom rail 11 of the screen frame by means of the screws 12 in the vertical leg 13 of the L. The horizontal leg 14 bears against the lower window frame member 15 and forms the pocket 16 into which the water table 10 on the window is free to extend when the window is closed as 55 shown in Figure 3. This closes an opening which would otherwise be left between screen and frame upon the withdrawal of the water table when the sash is open.

Having thus described my invention, what I claim as new and desire to secure by Letters Patent, is:—

60 1. In a screen for use with a metallic win-

dow frame, said screen being larger than said frame in at least one dimension, means for holding said screen thereagainst on the outside, said means comprising bent sheet metal members, one portion of each of which is adapted to be fastened against the frame of said screen and the other portion of which is adapted to lie inside of the window frame and against the inner face thereof.

70 2. In a screen for use with a metallic window frame, said screen being larger than said frame in at least one dimension, means for holding said screen thereagainst on the outside, said means comprising bent sheet metal members, one portion of each of which is adapted to be fastened against the frame of said screen and the other portion of which is adapted to lie inside of said window frame and against the inner face thereof, and means for slidably attaching at least one of said members to said screen.

75 3. In a screen for use with a metallic window frame, said screen being larger than said frame in at least one dimension, means for holding said screen thereagainst on the outside, said means comprising bent sheet metal members, one portion of each of which is adapted to be fastened against the frame of said screen and the other portion of which is adapted to lie inside of said window frame and against the inner face thereof, and means for slidably attaching at least one of said members to the screen, said inner faces of said members being bent outwardly at the bottom to rest upon the ledge of said window frame.

80 4. In a screen for use with a metallic window frame, said screen being larger than the opening in said frame in one dimension, fastening members attached to said screen to hold it against said frame on the outside, said members extending within said opening and bearing against the inside of said frame.

85 5. In a screen for use with a metallic window frame, said screen being larger than the opening in said frame in one dimension, fastening members attached to said screen to hold it against said frame on the outside, said members adapted to extend within said opening and to bear against the inside of said frame, said members adapted to lie alongside of said frame opening and to be oppositely disposed whereby movement of said screen will be inhibited in one direction.

90 6. In a screen for use with a metallic window frame, said screen being larger than the opening in said frame in one dimension, fastening members attached to said screen to hold it against said frame on the outside, said members adapted to extend within said opening and to bear against the inside of said frame, said members adapted to lie alongside of said frame opening and to be oppositely disposed whereby movement of said screen

will be inhibited in one direction, said members equaling in length the sides of said opening along which they are disposed, whereby abutment of the ends of said members against the adjacent sides of said opening will prevent movement of said screen in the other direction.

5. In a screen for use with a window frame, said screen being larger than the opening in said frame in one dimension, fasteners to hold said screen against said frame on the outside and adapted to extend within and abut said frame on the inside.

10. In a screen for use with a metallic window frame, said screen being larger than the opening in said frame in one dimension, fasteners to hold said screen against said frame on the outside and adapted to extend within and abut said frame on the inside, said fasteners being of spring metal whereby the abutment of the assembly against the outside and the inside of the window frame is tightened by spring tension.

15. In a screen for use with a window frame, said screen being larger than the opening in said frame in one dimension, fasteners to hold said screen against said frame on the outside by extending within and abutting said frame on the inside, said fasteners being disposed to prevent movement of said screen to uncover said opening.
